TABLE

Marion Joseph Madey, Park Ridge, Ill., assignor to Poster Products Inc., Chicago, Ill., a corporation of Illinois
Filed Feb. 23, 1967, Ser. No. 618,147
7 Claims. (Cl. 312—140)

ABSTRACT OF THE DISCLOSURE

A table is assembled from shaped, horizontal and vertical edge connecting members, preferably made of extruded aluminum, secured to resin coated plywood or other sheet material, characterized especially by side edge connecting members, and optionally front and rear edge connecting members, each of said side edge connecting members having a right angle portion, one side of said right angle portion extending upwardly, the other side of said right angle portion extending inwardly, said inwardly extending portion having at its inner end a downwardly extending portion at right angles, said upwardly extending portion having at its upper end an inwardly and downwardly extending portion.

One of the objects of the invention is to provide a new and improved table which can be readily assembled and is especially useful in stores and showrooms.

Another object of the invention is to provide a new and improved table made from resin coated plywood or other similar sheet material which is susceptible to scratching and wherein the scratching of the surface is avoided by a simple and unique assembly structure.

A further object of the invention is to provide structural members for a table which are especially useful in making tables from resin coated plywood and similar sheet materials.

Other objects and advantages of the invention will appear from the following description in conjunction with the accompanying drawing in which

FIG. 1 is a perspective view of one form of table provided in accordance with the invention;

FIG. 2 is a perspective view of a portion of a back edge connecting member of the table shown in FIG. 1;

FIG. 3 is a perspective view of a portion of a side edge connecting member of the table shown in FIG. 1;

FIG. 4 is a perspective view of a portion of a front corner member of the table shown in FIG. 1;

FIG. 5 is a perspective view of a portion of an upper guide rail member for sliding doors in the table shown in FIG. 1;

FIG. 6 is a perspective view of a portion of a lower guide rail member for sliding doors of the table shown in FIG. 1;

FIG. 7 is a perspective view of a portion of a front edge connecting member of the table shown in FIG. 1;

FIG. 8 is a perspective view of a corner member for the table shown in FIG. 1; and

FIG. 9 is a perspective view of a portion of a back corner member of the table shown in FIG. 1.

In its essential features, the table shown in the drawing comprises a table top, a pair of opposing side walls and opposing elongated side edge connecting members, each comprising a right angle portion, one side of said right angle portion extending upwardly and forming an outer abutment for said table top, the other side of said right angle portion extending inwardly and supporting a lower outer edge of said table top, said inwardly extending portion having at its inner end a downwardly extending portion forming a right angle with said inwardly extending portion, the upper edge of said table

2

side walls each abutting the lower side of said inwardly extending portion of one of said side edge connecting members and the outer sides of said downwardly extending portion of each of said side edge connecting members abutting the upper inside part of one of said side walls, said upwardly extending portion of each of said side edge connecting members having at its upper end an inwardly and downwardly extending portion terminating at the upper side of said table top.

10 Where the table has a back wall, as in the embodiment illustrated in the drawing, the table top is connected to the back wall by a back edge connecting member which is identical in structure to the side edge connecting members. The table can also have a front edge member connected to the table top and similar to the side edge connecting members. In some cases where the table has no front wall, the downwardly extending portion of the front edge member can be removed. Thus, in the embodiment shown in the drawing, the front of the table is provided with sliding doors which constitute the front wall and these are adapted to open and close on suitable guide rails in a well known manner. In this type of structure, the downwardly extending portion of the front edge member can be omitted.

25 As shown in the drawing, where the table has a back wall, the back wall and the side walls are connected by vertically disposed corner members. The front of each of the table side walls is also preferably protected by a vertically disposed corner member. The upper corners 30 of the table are provided with corner members which interfit with the edge connecting members.

In the specific structure shown in the drawings, the table top 1 is connected by means of side edge connecting members 2 and 3 to side walls 4 and 5. A back wall 6 is secured to a back edge member 7. The side wall 4 is connected to the back wall 6 by means of a vertically disposed corner member 8 as shown in FIG. 9. The front of each of the side walls 4 and 5 is protected by a vertically disposed corner member 9 as shown in FIG. 4.

40 A bottom 10 is secured to the side walls 4 and 5 and to the back wall 6 and the table is supported by means of four legs 11, which are secured to the bottom 10. Corner members 12 are provided at each of the four corners connecting the edge members around the top 45 of the table.

In the embodiment shown in the drawing, the front of the table comprises sliding doors 13 and 14 which are mounted in a known manner between an upper guide rail 15 and a lower guide rail 16. The upper front edge 50 of the table is provided with an edge connecting member 17 as shown in FIG. 7 which is connected to the table top 1.

The top, the side walls and the back wall are all fastened to the various edge members in any suitable manner, for example, by means of screws. Thus, the back wall 6 is held in place by means of screws passing through the holes 18 as shown in FIG. 2. The side wall 5 is held in place by means of screws passing through the holes 19 as shown in FIG. 3. The table top 1 is held in place by means of screws passing through the holes 20 as shown in FIG. 2 or the holes 21 as shown in FIG. 3.

60 Referring to FIG. 3, it will be seen that the edge connecting member 3, which is preferably made of extruded aluminum, has the shape of a right angle at 22. One side 65 23 extends inwardly a distance corresponding substantially to the thickness of the side wall 5. At its inner end a downwardly extending portion 24 forms another right angle. The top of the side wall 5, therefore, abuts against the lower side of the inwardly extending portion and the upper inside part of the side wall 5 abuts against the outer surface of the downwardly extending portion. The 70

other side 25 of the right angle 22 extends upwardly in a vertical plane, then inwardly at 26, and downwardly at 27. The lower end of the downwardly extending portion 27 is spaced from the upper side of the inwardly extending portion 23 a distance substantially equal to the thickness of table top 1. Hence, the portion of the edge member 25 which extends above the table top 1, together with the inwardly and downwardly extending portions 26 and 27, form a guide rail at one side of the table top. Similarly, the back edge member 7, the other side edge member 2 and the front edge member 17 form guide rails which completely surround the table top and retain objects placed thereon.

Referring to FIG. 8, the corner member 12 is preferably made of extruded aluminum and consists of a solid block portion 28 and projecting portions 29, 30, 31 and 32. The latter are sized to fit within the opening at the ends of the edge connecting members. Thus, the projecting portions 29 and 30 are adapted to fit within the opening formed by the sides 23, 25, 26 and 27 of the edge connecting member 3 shown in FIGURE 3. It will be understood that the top 1 is cut away at the corner a sufficient distance to accommodate the projecting portions of the corner member 12.

As shown in FIG. 9, the vertically disposed back corner members 8 consist of two right angle shaped members having sides 33, 34, 35 and 36 and connected by another member 37. The sides 35 and 36 are parallel and are spaced apart a sufficient distance to accommodate a side wall 4. The sides 33 and 34 are likewise parallel and are spaced apart a distance sufficient to accommodate the back wall 6.

With reference to the corner members 28, it should be noted that the projecting portions 29, 30 and 31, 32 can each be combined into a single projecting portion. However, by employing a plurality of projecting portions sufficient resilience is provided to make it easier to engage the corner members with the associated edge connecting members. The outer upper corner 38 of each corner member 28 is preferably bevelled as shown in FIG. 8.

The invention makes it possible to assemble a table using plywood panels, for example, panels made of $\frac{3}{4}$ " or $\frac{7}{8}$ " plywood coated with any suitable type of coating, for example, melamine formaldehyde resins or urea-formaldehyde resins, which are commonly available in commercial forms, such as Formica. The assembly can be fitted without scratching the resinous surface of the panels. Furthermore, all of the required components are readily manufactured by extrusion processes. While it is preferable to use extruded aluminum components, it will be recognized that steel or other metals and even very strong other types of materials can likewise be employed.

The invention is hereby claimed as follows:

1. A table comprising a table top, side walls, and opposing elongated side edge connecting members each comprising a right angle portion, one side of said right angle portion extending upwardly and forming an outer abutment for said table top, the other side of said right angle portion extending inwardly and supporting a lower

outer edge of said table top, said inwardly extending portion having at its inner end a downwardly extending portion forming a right angle with said inwardly extending portion, the upper edge of said table side walls abutting the lower side of said inwardly extending portion and the outer side of said downwardly extending portion abutting the upper inside part of said side walls, said upwardly extending portion having at its upper end an inwardly and downwardly extending portion terminating at the upper side of said table top.

10 2. A table as claimed in claim 1 in which said edge connecting members are made of extruded metal.

15 3. A table as claimed in claim 1 which also has a back wall connected to said top by back edge connecting members identical in cross sectional shape to said side connecting members.

20 4. A table as claimed in claim 3 in which said side and back edge connecting members are joined together by corner members.

25 5. A table as claimed in claim 4 in which said corner member has projecting portions on two adjacent sides interfitting in openings in adjacent edge connecting portions.

30 6. A table as claimed in claim 1 which also has a back wall connected to said top by a back edge connecting member identical in cross sectional shape to said side connecting members, has a front edge connecting member secured to said top and has back vertically disposed corner connecting members secured to said back wall and on each back corner to said side walls, said back corner connecting members each comprising a pair of right angle members connected at the inside of one of said angles and the outside of the other of said angles by a third member with the sides of said angles being parallel and spaced apart a sufficient distance to receive the back wall and one of the side walls of said table.

35 7. An edge connecting member for connecting a table top and side wall, said connecting member being formed of rigid sheet material having a right angle portion, one side of said right angle portion extending upwardly, the other side of said right angle portion extending inwardly, said inwardly extending portion having at its inner end a downwardly extending portion at right angles, said upwardly extending portion having at its upper end an inwardly and downwardly extending portion.
